UNITED STATES PATENT OFFICE

OSCAR A. BOEHM, OF NEW YORK, N. Y.

POCKET-LAMP.

1,127,856.

Specification of Letters Patent.

Patented Feb. 9, 1915.

Application filed April 18, 1914. Serial No. 332,214

To all whom it may concern:

Be it known that I, OSCAR A. BOEHM, a citizen of the United States, residing at New York city, county and State of New York, have invented a new and Improved Pocket-Lamp, of which the following is a specification.

This invention relates to an electric pocket lamp of novel construction which permits a ready exchange of the light bulb and battery, emits a maximum amount of light for the electric current consumed, while its constituent parts are so arranged that they occupy but a minimum space.

The invention further comprises other novel features of construction as more fully brought out in the appended specification and claims.

In the accompanying drawing: Figure 1 is a vertical section through a pocket lamp embodying my invention; Fig. 2 a transverse section on line 2—2 Fig. 1; Fig. 3 a top view of the lamp with the lid opened; Fig. 4 a section on line 4—4, Fig. 1, with the battery omitted, and Fig. 5 a cross section through the light bulb.

The casing A of my improved pocket lamp comprises essentially a pair of parallel flat sides 10, rounded ends 11, and an integral bottom 12. Casing A is adapted to accommodate a similarly shaped dry cell or battery 13, that rests on bottom 12, while the casing extends upwardly beyond battery 13, to here form a compartment 14 for the reception of the light bulb 15 and the contact springs 16, 17 of the battery. To one of the flat sides 10 of casing A is hinged at 18 a lid 19 which is provided with a springy finger piece 20 adapted to engage a bead 21 formed on the other side 10 of the casing. To the inner face of lid 19 is soldered or otherwise connected a spring clamp 22 for the engagement with the socket 23 of bulb 15, the clamp 22 being so disposed relatively to the lid that bulb 15 lies flat against the latter, *i. e.* that the longitudinal bulb axis extends parallel to the plane of the lid. The filament 24 is exposed through an opening 25 of the lid, while the central contact 26 of the bulb is normally engaged by the contact spring 16 of battery 13. In order to increase the light effect of bulb 15 without the use of a reflector, its lower portion 27 is formed of opal glass while its upper portion 28 is formed of ordinary transparent glass. In manufacturing these bulbs, it is

preferred to use glass tubing that is partly composed of opal glass and transparent glass, both kinds of glass being united along diametrically opposed lines 29 which occupy a common plane with that of filament 24 as indicated in Fig. 5.

It may here be stated that with the pocket lamps hitherto generally used, the longitudinal axes of the light bulbs extend at right angles to the plane of the lamp tops, said arrangement requiring the use of tipless bulbs, the manufacture of which is more expensive than that of bulbs having the usual end tips. As with my construction the side of the bulb only, is exposed through opening 25, the bulb may have an end tip 30 so that the cost of the pocket lamp is correspondingly reduced. As furthermore upright bulbs occupy more space above cell 13 than is required for my bulb which extends in parallelism to the lid 19, the longitudinal dimension of the casing is considerably reduced, which reduction in length is extremely important with lamps designed to be carried in the vest pocket.

In order to permit a ready removal of cell 13 through the opened top of casing A without interfering with the movable stud 31 for lighting the bulb, the following construction has been devised:

One of the rounded ends 11 of casing A is provided with a longitudinal enlargement or pocket 32, to the inner side of which is riveted or otherwise secured the lower end 90 of a flat spring 33 carrying a push button 34 that projects outward through a corresponding aperture 35 of said enlargement. In proximity to the upper end of spring 33, there is secured thereto an inwardly extending eye 36 into which is removably fitted a resilient bar 37 accommodated within pocket 32 and carrying near its inwardly deflected upper end 38, the stud 31 hereinabove referred to. It will be seen that by pressing button 34, the latter transfers its movement through spring 33 and bar 37 to stud 31, thereby effecting an engagement between the latter and contact 17 and thus closing the bulb circuit. If a worn cell 13 is to be replaced by a fresh cell, lid 19 is opened and the casing A is turned upside down so that the cell will slide outward, thereby taking along bar 37 owing to the engagement of the cell with stud 31. After the fresh cell has been introduced, bar 37 is slid into eye 36 until it occupies the pos-

tion shown in Fig. 1 whereupon lid 19 is closed and the lamp is again ready for use.

I claim:

1. A pocket lamp comprising a casing, a cell inclosed thereby, an apertured lid adapted to close the casing, a light bulb removably secured to the lid and exposed through the lid aperture, the longitudinal axis of the bulb extending in substantial parallelism with the lid, and means for conductively connecting the cell and bulb.
2. A pocket lamp comprising a casing, a cell inclosed thereby, an apertured lid adapted to close the casing, a spring clamp on the lid, a light bulb removably engaging said clamp and exposed through the lid-aperture, the longitudinal axis of the bulb extending in substantial parallelism with the lid, and means for conductively connecting the cell and bulb.
3. A pocket lamp comprising a casing, a cell inclosed thereby, an apertured flat lid hinged to the casing, a spring clamp on the lid, a light bulb removably engaging said clamp and exposed through the lid-aperture, the longitudinal axis of the bulb extending in substantial parallelism with the lid, and means for conductively connecting the cell and bulb.
4. A pocket lamp comprising a casing, a

cell inclosed thereby, an apertured lid adapted to close the casing, a light bulb removably secured to the lid and having an inner opal glass portion and an outer transparent glass portion that is exposed through the lid aperture the longitudinal axis of the bulb extending in parallelism to the lid, and means for conductively connecting the cell and bulb.

5. In a pocket lamp, a casing, a cell inclosed thereby and having a contact, a spring secured to the casing, a push bottom and an eye on said spring, a resilient bar engaging the eye, and a stud on said bar that is adapted to engage the cell-contact.

6. In a pocket lamp, a casing having rounded ends, a pocket formed at one of said ends, a cell inclosed within the casing and having a contact, a spring secured to the inner side of said pocket, a push button and an eye carried by said spring, a resilient bar removably engaging the eye and received within the pocket, and a stud on said bar that is adapted to engage the cell-contact.
